DISPENSING NOZZLE FOR A COLLAPSIBLE TUBE OR THE LIKE

Henry Gerson, Fairlawn, N.J., assignor to Tri-Chem, Inc.
Belleville, N.J., a corporation of Delaware

Filed Mar. 25, 1968, Ser. No. 11,110

Term of patent 14 years

Int. Cl. D9—99, 02
U.S. Cl. D9—275

FIG. 1.

FIG. 2.

FIG. 3.

FIG. 4.

FIG. 5.

FIGURE 1 is an elevational view of a dispensing nozzle for a collapsible tube or the like, showing my new design;

FIGURE 2 is an elevational view looking from the right of FIGURE 1;

FIGURE 3 is a top plan view;

FIGURE 4 is a bottom plan view; and

FIGURE 5 is a sectional view thereof taken on line 5—5 of FIGURE 1.

I claim:

The ornamental design for a dispensing nozzle for a collapsible tube or the like, as shown.
